HOIST CRANE CONSTRUCTION

Robert J. Harry, Alliance, Ohio

Application January 12, 1939, Serial No. 250,577

8 Claims. (Cl. 254—184)

This invention pertains to a new and improved operating mechanism arrangement and/or layout for a hoist crane, and particularly, to a new and improved actuating mechanism therefor.

Previous to the present invention, as explained in my copending application Serial No. 250,578, filed January 12, 1939, entitled "Hoist crane construction," it has heretofore been customary to provide worm gears where the advantages of an intertimed relationship are desired between hoist drums, and also where assurance of protection is provided against the failure of one of the hoist drum or driving mechanisms.

An object of the present invention has been to provide a new and improved layout or operative arrangement for hoist drums in a crane construction.

Another object of my invention has been to devise a new and improved intertimed and interlocking drive arrangement for crane hoist apparatus.

A further object has been to provide an actuated relationship of hoist drums in a crane construction that embodies the advantageous features of a worm gear arrangement without disadvantageous features thereof.

A still further object has been to provide a hoist mechanism arrangement wherein drum gears are interlocked and the motors are connected in such a manner that the arrangement is protected from damage due to an unequal actuation or stoppage of the motivating mechanisms.

These and many other objects of my invention will appear to those skilled in the art from a study of the drawings, the description thereof, and the appended claims.

In the drawings:

Figure 1 is a top plane view of a hoist crane operating mechanism embodying novel features of the present invention;

Figure 2 is an enlarged side view in elevation of a ratchet gear employed in the arrangement of Figure 1; and

Figure 3 is a sectional view in elevation taken along the line III—III of Figure 2.

Although any suitable form of crane framework construction may be employed, I have shown a transversely extending framework 10 having flange track wheels 11 journaled within housing portions at opposite corners thereof and driven by motors 15, oppositely extending armature shafts 13, and gear reduction units 14.

Oppositely located housings 20 of generally rectangular outline are mounted on the frame 10

adjacent opposite sides thereof and suitably journaled hoist drums 22. As shown, a pair of hoist drums 22 is journaled in each housing 20 and cooperates with a cable sheave 23 operably mounted on the shaft 24 on the framework 10; the sheaves 23 are preferably mounted below and in substantial alignment with the center line between each pair of drums. Other suitable arrangements may be employed.

10 Each drum 22 is provided with a large gear wheel 25 adjacent its inner end that meshes with a similar gear wheel of the other drum of the same pair. Each of the drum gears 25 is in turn actuated and driven by a drive pinion 26 mounted on opposite ends of a drive shaft 27. Oppositely-positioned drive shafts 27 are journaled at opposite ends within the opposite housings 21 mounted on the framework 10.

Individual motors 30 having suitable brake drums 31, shaft couplings 32, armature shafts 33, and armature pinions 35, drive a gear mechanism that is mounted in housing 34 and that, in turn, drives each of the oppositely-positioned drive shafts 27.

15 As will be noted, the drive shafts 27 are positioned at opposite ends of the framework and are driven by individual motors; the motors, in turn, are connected through the drive shafts 27, the drive pinions 26, and the drum gears 25.

20 The gear mechanism within the housing 34 comprises a jack shaft 37 journaled therein and having a gear 36 meshing with armature pinion 35 and driving a jack shaft pinion 38 that meshes with a ratchet gear 39.

25 As will be noted, the drive shafts 27 are positioned at opposite ends of the framework and are driven by individual motors; the motors, in turn, are connected through the drive shafts 27, the drive pinions 26, and the drum gears 25.

30 The gear mechanism within the housing 34 comprises a jack shaft 37 journaled therein and having a gear 36 meshing with armature pinion 35 and driving a jack shaft pinion 38 that meshes with a ratchet gear 39.

35 The ratchet gear construction is shown particularly in Figures 2 and 3 of the drawings. It includes a main body portion 39 having gear teeth about its periphery and having bearing portions 41 and 42 that are journaled with respect to a secondary, inner, ratchet tooth wheel portion 40. The latter is preferably secured or feathered to the drive shaft 27, see keyway 43, and is provided with a peripheral annulus bearing portion 44 that abuts against bearings 42 and is held in position by a plurality of radially extending and spaced-apart positioning clamps 45. The clamps 45 are of angular construction and at their outer ends terminate in offset portions 46 that receive a resiliently mounted bolt construction 47 extending from the gear portion 39. In this manner, the ratchet wheel portion 40 is resiliently held in position with respect to the gear portion 39 in the plane of its rotative axis by the spring mechanism 47.

40 Rachet pawls 50 are pivotally mounted at 51

45

on inwardly extending mount portions of the gear 39. Each pawl is provided with an extending guide pin 52 at its rear end that is adapted to move along a slotted portion 53 of the mount construction. The pawls also engage with the teeth indentations 48 of the ratchet wheel 40 and are held in an operative relationship with respect thereto by substantially radially extending springs 55. The springs 55 are positioned between a stud 54 of an inner peripheral portion of the gear 39 and indentations 49 within faces of the pawls 50.

From a study of the above construction, it will appear that a rotation of the gear wheel 39 in a clockwise direction in Figure 2 will produce a corresponding rotation of the inner or pawl wheel 40, and thus, of the drive shaft 27, while a counter-clockwise rotation will be permitted without actuation of the shaft 27. That is, in the latter case, the pawls 50 will slip over the pawl teeth 48 and permit relative movement between the two parts of the ratchet gear mechanism. This arrangement thus permits the motors 30 to positively actuate the directly interlocked pairs of hoist drums 22, but will prevent damage to the apparatus and connections if one motor is stopped or started before the other by reason of the permissive relative movement between the pawl and ratchet portions.

As will appear, the motors of my arrangement are connected for synchronous operation in hoisting, and in case of the failure of one motor the ratchet gears will permit the load to be raised by the other motor. In normal hoisting with two motors, premature setting of the brakes of one motor will not set up inertia stresses in the hoisting mechanism. As relative movement is permitted between the motors by reason of the ratchet gears and as one motor tends to slow down, so that its speed is slower than the other motor, the load is supported by the motor having the greater relative speed. When both sets of motor brakes are applied and the motors brought to rest, both sets of brakes can be effective in holding the load. In lowering, the speed of the descending load is determined by the speed of the slower motor, as the load on the hooks keeps the ratchets in engagement in the slower motor gear train. The application of dynamic braking regulates the speed of the descending load. This means that the load cannot be lowered when one motor is stopped, which is just the opposite to the hoisting sequence, where the load can be lifted by one motor when the other is stopped.

The premature setting of the brakes of one motor, when lowering, will apply retarding torque to the load and cause deceleration, but the ratchet gears prevent the other motor from setting up inertia stresses in the lowering mechanism, as the relatively faster motor cannot apply torque in the lowering mechanism due to the ratchet gears; this causes the slower motor to take the load in lowering and the faster motor to take the load in hoisting. In lowering, the speed is determined by the slower motor, and in hoisting, the speed is determined by the faster motor.

When I speak of the axis of the individual drums or the axes of the drum pairs or portions of the same, I have reference to the axis or axes about which the drum or drum pairs turn or rotate. The same is true as to shafting and other operating and drive connections and members as defined in the claims. When I speak

of "interlocked drums" in the specification, I have reference to intermeshed or intermeshing drums which are provided with suitable means such as drum gears for, in effect, locking them in such a manner that their operation is intergeared and that they are separately actuated by suitable members.

Although for the purpose of illustration, I have shown a form of my invention that provides a suitable type of motor movement and interlocking drum relationship and permits the motivating mechanism to operate the drum pairs without danger due to unlike characteristics of the motors or due to uneven stopping or starting action, it will be apparent to those skilled in the art that many other suitable arrangements may be employed and that various modifications, additions, subtractions, etc., may be made to the mechanism shown and described without departing from the spirit and scope of the invention as indicated by the appended claims.

I claim:

1. In a hoisting crane, pairs of hoisting drums, each drum having a gear secured thereto, the drums of each pair being operably intermeshed through said gears and having a portion of their axes in a side-by-side relationship, a pair of actuating motors for said drums, said motors being positioned adjacent end portions of said drums, each motor having a drive member extending in substantially the same direction as the above-defined portion of the drum axes, a member operably connecting a drum of one pair to a drum of the other pair, a second member operably connecting the other drums of the pairs together, means operably connecting one of said members to one of said motors, and independent means operably connecting the other of said members to the other of said motors for actuating said drums.

2. In a hoisting crane, spaced-apart pairs of hoisting drums, each drum having a gear secured thereto, drums of each drum pair being operably intermeshed through said gears and having a portion of their axes in a side-by-side relationship, a pair of actuating motors for said drums positioned in the spacing between said drum pairs adjacent end portions of said drums, each motor having a rotating axis extending substantially in the same direction as the above-mentioned portion of the drum axes, means operably connecting one of said motors to a drum of each pair, and means operably connecting the other of said motors to the other drums of each pair, each of said means being independent of the other.

3. In a hoisting crane, spaced-apart pairs of hoisting drums, each drum having a gear secured thereto, the drums of each pair being operably intermeshed through said gears and having a portion of their axes in a side-by-side relationship, a pair of actuating motors for said drums in the spacing between said drum pairs, said motors being positioned adjacent end portions of said drums, each motor having a rotating axis extending substantially in the same direction as the above-mentioned portion of the drum axes, one of said motors having its front end portion facing one pair of drums, the other of said motors having its front end portion facing the other pair of drums, means operably connecting one of said motors to one drum of one pair and to an opposite drum of the other pair, said means permitting relative movement in one di-

rection between said motor and said drums to which it is operably connected, and additional means operably connecting said other motor to the other drum of the one pair and to an opposite drum of the other pair.

4. In a hoisting crane as defined in claim 3, wherein said additional means also permits relative movement in one direction between said other motor and the drums to which it is operably connected.

5. In a hoisting crane, spaced-apart pairs of hoisting drums, each drum having a gear secured thereto, the drums of each drum pair being operably intermeshed through said gears and having a portion of their axes in a side-by-side relationship, a pair of actuating motors for said drums, said motors being positioned between said pairs of hoisting drums adjacent end portions of said drums, each motor having a rotating axis extending substantially in the same direction as the above-mentioned portion of the axes of said drums and being in a substantially parallel relationship with the rotating axis of the other of said motors, members extending across the spacing between said drum pairs and operably connecting opposite drums of each pair together, and intermeshing gear means operably connecting one motor to one of said members and operably connecting the other motor to the other of said members, said connections being independent of each other and having means for permitting relative movement in one direction between at least one of said motors and said members.

6. In combination with a traveling hoisting crane adapted to move longitudinally from one location to another and having a frame extending transversely of its direction of movement, spaced-apart pairs of hoisting drums operably

positioned at opposite sides of said frame, the drums of each pair having a portion of their axes in a side-by-side relationship, each drum of each pair having a gear intermeshing with a gear of the other drum of the same pair, a pair of motors on said frame in the spacing between said drum pairs, said motors being positioned adjacent end portions of said drums and having drive members extending in a substantially end-to-end relationship with said drum pairs, the axes of said drums extending substantially transversely of the direction of travel of said crane, a member having gear means adjacent opposite ends thereof operably connecting together a drum of one pair with an opposite drum of the other pair, a second member having gear means adjacent opposite ends thereof operably connecting the other drum of one pair to the other and opposite drum of the other pair, spur gear means operably connecting the drive member of one motor to one of said connecting members, and independent spur gear means operably connecting the drive member of the other motor to the other of said connecting members.

25 7. In a combination as defined in claim 6, wherein at least one of said spur gear means is provided with means permitting relative movement in one direction between the associated motor drive member and the connecting member.

8. In a combination as defined in claim 6 wherein said connecting members extend substantially transversely of the direction of travel of said crane and have a spaced-apart relationship with respect to each other substantially corresponding to a dimension of a drum pair taken substantially longitudinally of the direction of travel of said crane.

ROBERT J. HARRY.
